UNITED STATES PATENT OFFICE.

MONTAGUE REDGRAVE, OF JERSEY CITY, NEW JERSEY.

DESIGN FOR A BAGATELLE-BOARD.

SPECIFICATION forming part of Design No. 29,047, dated July 12, 1898.

Application filed January 18, 1897. Serial No. 619,685. Term of patent 14 years.

To all whom it may concern:

Be it known that I, MONTAGUE REDGRAVE, a citizen of the United States, residing at Jersey City, in the county of Hudson and State 5 of New Jersey, have invented and produced a new and original Design for a Bagatelle-Board; and I do declare the following to be a full, clear, and exact description of the same, reference being had to the accompanying 10 drawing, forming a part thereof.

The drawing is a view in perspective of a bagatelle-board, showing my design.

The leading feature of my design consists in the general shape or configuration of my 15 bagatelle-board, as shown in the drawing.

A represents the general ground, which is a rectangular parallelogram in form of the board; B, the rim, of similar outline; C, the curved guard at the upper end, and H the 20 straight inner wall of the alley, the parallel part of the rim forming the outer wall thereof. A plate I of rectangular outline covers a

part of the alley and its walls. In this plate is a longitudinal slot J.

Within the middle part of the board, as 25 usual, are distributed the pockets, pins, disks, and bells proper to the game in convenient locations and numbers. The pockets are designated E, the disks F, the pins D, and the bells G.

This detail description of my design relates 30 only to the shape, configuration, and appearance of the bagatelle - board, although the parts thereof are necessarily mentioned.

What I claim as new, and desire to secure 35 by Letters Patent, is—

The design for a bagatelle-board substantially as shown and described.

In testimony whereof I affix my signature in presence of two witnesses.

MONTAGUE REDGRAVE.
